UNITED STATES PATENT OFFICE.

ANTONI BRZYKCY, OF MINNEAPOLIS, MINNESOTA.

WINDOW-BRACKET.

No. 821,983.

Specification of Letters Patent.

Patented May 29, 1906.

Application filed January 2, 1906, Serial No. 294,039.

To all whom it may concern:

Be it known that I, ANTONI BRZYKCY, a citizen of the United States, residing at Minneapolis, in the county of Hennepin and State of Minnesota, have invented certain new and useful Improvements in Window-Brackets; and I do hereby declare the following to be a full, clear, and exact description of the invention, such as will enable others skilled in the art to which it appertains to make and use the same.

My invention has for its object to provide an improved window-bracket especially adapted to support in different ways the rollers of window-shades.

To the above ends the invention consists of the novel devices and combinations of devices hereinafter described, and defined in the claim.

In the accompanying drawings, which illustrate the invention, like characters indicate like parts throughout the several views.

Figure 1 is a view in elevation, showing portions of a window frame and sash and a shade supported from the window-frame by a pair of my improved brackets, the said parts being viewed from the inner side of the building. Fig. 2 is a vertical section taken approximately on the line $x^2 x^2$ of Fig. 1. Fig. 3 is a section taken approximately on the line $x^3 x^3$ of Fig. 1, some parts being broken away. Fig. 4 is a detail in edge elevation looking at the bracket shown in Fig. 2. Fig. 5 is an edge elevation of the bracket shown in Fig. 3, some parts being removed. Fig. 6 is a view, partly in elevation and partly in section, showing the bracket applied in a different way than illustrated in Fig. 1, some parts being broken away; and Fig. 7 is a detail in elevation, showing the right-hand bracket and right-hand end of the shade-roller in the arrangement illustrated in Fig. 6.

The numeral 1 indicates the window-frame, the numeral 2 the upper sash, the numeral 3 a window-shade, and the numeral 4 the shade-roller, all of the usual construction. The shade-roller being of standard construction is formed or provided at one end with a rigidly-secured round gudgeon 5 and at its other end with a flat spring-actuated gudgeon 6.

Each bracket is made up of a supporting-rod 7 and a body-section 8, adjustably secured thereto. The supporting-rod 7 at one end is preferably in the form of a lag-screw 8^a, and at its other end it is preferably bent, as

shown at 9 in Figs. 2 and 3 or at 10 in Figs. 6 and 7. When bent as shown at 9, the projecting end of a pair of rods 7 are adapted to support a curtain-pole of considerable size, 60 and when bent as shown at 10 they are adapted to be passed through perforations in the ends of a curtain-rod.

The body portion 8 is formed from a quite thin strip of metal having parallel edges, and 65 one end thereof is preferably bent around the body of the screw-rod 7 and is adjustably clamped thereto by a thumb-screw 11, having a nut 12. The bracket-body 8, that is to engage and support the flat trunnion 6 of the 70 shade-roller, is formed near its lower end with a pair of elongated seats 13, that intersect each other at right angles, and at one edge it is slit at 14. The narrow portion of the body 8 on one side of the slit 14 is bent outward in 75 one direction, as shown at 15, and the body portion on the other side of said slit is pressed outward in an opposite direction at 16, so as to leave an elongated seat 17, that extends in the plane of the said body 8. (See Figs. 2 80 and 4.)

The body 8 of the bracket which is to engage and support the round gudgeon 5 of the shade-roller is formed like the body just described, except instead of the crossed seats 13 85 it is provided with a single round perforation 18 and that the bulged portions 15 and 16 are bent to form a round seat 19.

The bracket above described is capable of use and is adapted to be applied and supported in several different ways. In Figs. 1 and 2 the screw-rod 7 is shown as screwed into the cap-blocks of the window-casing and as projecting horizontally inward therefrom. In this arrangement the round trunnion 5 of 95 the shade-roller is seated in the perforation 18 in the body of the right-hand bracket, while the flat trunnion 6 thereof is seated in one of the crossed slots 13 of the body of the left-hand bracket. In Figs. 6 and 7 the 100 screw-rods are screwed into the inner edges of the window-casings, and the round trunnion of the roller is seated in the round seat 19 of the body of the right-hand bracket, while the flat trunnion of said roller is seated 105 in the elongated seat 17 in the body of the left-hand bracket.

In my prior patent, No. 731,540, issued June 23, 1903, I have disclosed a window-shade bracket in some respects like the 110 bracket herein shown, but in which the body of the bracket was stamped or cut with an irreg-

ular outline and then bent, necessitating a great waste of material. The body of the bracket of my present application is made from ribbon-like strips of metal having parallel edges, and hence there is practically no waste of material. The device, while of small cost, has been found efficient for the purposes had in view.

What I claim, and desire to secure by Letters Patent of the United States, is as follows:

A window-bracket comprising a supporting-rod and a body portion adjustably sup-

ported therefrom, which body portion is formed from a thin strip of metal having parallel edges, the said body being slit at 14 and 15 being pressed in reverse directions at 15 and 16, to form a trunnion-seat, substantially as described.

In testimony whereof I affix my signature in presence of two witnesses.

ANTONI BRZYKCY.
